UNITED STATES PATENT OFFICE

2,543,571

GRAPE CRUSHER AND STEMMER

Abele Ferrari, Healdsburg, Calif.

Application January 8, 1947, Serial No. 720,805

1 Claim. (Cl. 146—76)

1 This invention relates to machines designed to crush and stem grapes so as to extract the pulp and juice therefrom.

More specifically, the invention relates to improvements in machines of this character which embody the use of blades or paddles rotating in a drum that crush and stem the grapes.

The primary object of the invention is to provide an improved rotating blade apparatus, embodying the use of different types of blades rotating in the drum, one set of blades being formed so as to be particularly adapted for crushing the grapes, without crushing the stems, and the other set being particularly adapted to complete the crushing, to remove the dry stems from the pulp, and to eject the stems from the machine.

Another important object of the invention is to provide improved drive means for rotating the blades and the drum at different speeds, and an improved feed and discharge mechanism.

With the foregoing and other objects in view which will appear as the description proceeds, the invention consists of certain novel details of construction and combinations of parts, herein-after more fully described and pointed out in the claim, it being understood that changes may be made in the construction and arrangement of parts without departing from the spirit of the invention as claimed.

Referring to the drawings

Figure 1 is a longitudinal vertical sectional view through a machine constructed in accordance with the invention, in which the blade, drive, feed, and discharge apparatus embodied therein are shown in elevation.

Figure 2 is an end elevational view, showing the outlet end of the drum.

Figure 3 is a sectional view taken substantially on line 3—3 of Figure 1.

Figure 4 is a sectional view taken substantially on line 4—4 of Figure 1.

Figure 5 is a sectional view taken substantially on line 5—5 of Figure 1.

Referring to the drawing in detail, the machine embodied in the invention is supported in a suitable frame, including a base, the frame being designated generally by the character reference number 5, and being of substantially rectangular conformation when viewed in side or end elevation.

Supplying power to the machine is an electric motor 6, rotating a mainshaft 7 by means of belts 8 passing around the pulleys 9 on the mainshaft and the pulleys 10 on the motor, the mainshaft being journaled in ballbearings 11

mounted at the ends of the frame 5, and in a ballbearing 12 mounted on a cross bar 13 of the frame.

A portion of the mainshaft 7 extends through a hopper 14, in which grapes to be treated by the machine are deposited, and this portion of the mainshaft carries a worm conveyor 15, whereby the grapes are fed into a rotatable perforated drum with which the hopper communicates, and which has been indicated generally by the character reference numeral 16. Spaced rings 16' are peripherally disposed along the outer wall of the drum 16, and strengthen the construction of the drum.

Driven by the mainshaft 7 is the intermediate shaft 17, that is rotated by means of a chain 18 that passes around the sprocket 19 on the mainshaft, and the sprocket 20 on the intermediate shaft. In turn, chain 21 passing around 20 the sprocket 22 on the intermediate shaft, and around sprocket 23 on a pinion shaft 24 transmits rotary movement to the pinion shaft.

Mesning with the pinion 25 carried by the pinion shaft 24 is the ring gear 26 that rotates 25 the drum 16, the ring gear being coaxially aligned with the drum and fixedly connected thereto by a plurality of rods 27 which also extend through a brace wheel 28 that serves the purpose of bracing the connection under strain which 30 might be exerted thereupon.

Spaced brackets 29 extending inwardly from each side of the frame 5 carry wheels 30 on which the drum 16 rotates.

By reason of the reduction gearing described, 35 the drum 16 is adapted to rotate comparatively slowly, at a speed of approximately 7 revolutions per minute.

From the inlet end of the drum 16 to a point approximately intermediate its ends, the peripheral wall of the drum is formed with slot perforations 31 which are disposed in staggered parallel relation. Within this portion of the drum 16, there is mounted on the mainshaft 7 in equally spaced relation a plurality of spiders or radial arms 32. These spiders 32 are fixedly secured to the mainshaft 7, and are preferably each formed with four blades. Each of these four blades is disposed at a right angle to the adjacent blades of the same spider, and is pitched obliquely as is clearly shown by reference to Figures 1 and 3, so that attachments on the ends of the blades, which attachments will be described in detail herein-after, will move engaged material in a direction away from the inlet end of the drum.

55 Referring individually to each spider 32, there are mounted at the outer ends of opposed blades

curved crushing paddles 33, the other opposed blades of each spider 32 being provided with flat carrying paddles 34. The paddles 33 curve in a direction away from the direction of rotation of the drum 16 and spiders 32. Thus the leading faces of the crushing paddles 33 have a wiping action over the drum surface. This is to be distinguished from the action of the carrying paddles 34. The faces of the carrying paddles extend straight inwardly from the drum surface, so that the end edges only of said paddles, rather than portions of their leading faces, wipe over the drum surface. Grapes fed into the drum are crushed between the curved paddles 33 and the wall of the drum 16, but by reason of the construction embodied in the paddles 33, the stems of the grapes are not broken, which is desirable by reason of the fact that the stems contain an acid which is harmful to wine, which may be made from the grapes.

The carrying paddles 34 which follow each crushing paddle 33 on the same spider serve the function of moving the crushed grapes onto the next spider 32 or set of blades, where they are further crushed until they are moved past the spider 32 which is furthest from the inlet end of the drum 16.

As may be seen from Figures 1 and 3, the blades of the spiders 32 are arranged in staggered relationship, which guarantees steady continuity of function, and keeps the grapes evenly distributed in the drum, so that there will be no large masses of grapes accumulated therein which might result in an uneven distribution of strain on the machine. It is further to be noted from the drawing that the paddles 33 and 34 of said spiders 32 are short in length and spaced substantial distances from the paddles of the next adjacent spider, so that there are clear spaces between adjacent spiders into which the grapes move when passed from one spider toward the next one. As a result, during movement through these spaces the grapes are not subjected to any crushing action but the rotation of the drum continues to turn the grapes over so that by the time said grapes reach the next spider, they are again well mixed for further crushing.

During operation of the machine, the blades of the spiders 32 travel at a relatively high speed, which may be stated as approximately 400 revolutions per minute. At the same time, the reduction gearing hereinbefore described, whereby motion is transmitted to the drum 16, causes the drum 16 to rotate in the same direction as the blades, that is, counterclockwise when viewed as in Fig. 3, but as previously mentioned, at a reduced speed of about 7 revolutions per minute, and this arrangement between the blades and the drum is specifically adapted to prevent injury to the grape stems, and to keep the perforated drum wall clean. The blades 33 and 34 are of inflexible material.

Within the portion of the drum 16 that extends from the spider 32 most remote from the inlet end, to the other end of the drum, are mounted radial spiders 35, which have obliquely extended blades disposed at a right angle to their adjacent blades. There are preferably two of these spiders 35 and they are arranged in staggered relation, as is clearly shown by Figures 1 and 2.

Extending between the spiders 35 and secured to the blades thereof in spiraled relation, are stemming arms 36, which are adapted to receive the grapes from the crushing apparatus, and to clean the remainder of the juice and pulp there-

from, forcing the juice and pulp through round openings 37 disposed in staggered relation in the periphery of the drum 16, and which discharge the dry stems of the grapes from the open outlet end 38 of the drum.

As the pulp and juice are forced through the wall of the drum 16, they are received in a pan 39, which fully encloses the drum 16, in order that all pulp and juice forcibly ejected through the slotted and circular perforations will be retained and will move to the bottom of the pan. A hinged door 40 permits access to the pan and to the drum for cleaning purposes.

On the pinion shaft 24 is carried a sprocket 41 around which passes a chain 42 that also passes around a sprocket 43 on a feed shaft 44, the shaft 44 being rotatable in the pan 39, adjacent the bottom thereof. The portion of the feed shaft 44 within the pan 39 carries a right and left helical feed or worm conveyor 45, which is adapted to move the pulp and juice collecting in the bottom of the pan to the center thereof, where an outlet 46 is provided.

What is claimed is:

25 In a machine for crushing and stemming grapes, a crushing structure including a rotatable apertured drum; a main shaft extending through the drum; a plurality of spiders rotatable with and spaced longitudinally of the main shaft, said 30 spiders each including radial arms extending toward the wall of the drum, short paddles on some of the arms curved radially of the drum away from the direction of rotation of the drum, the leading faces of said paddles being partially in 35 wiping contact with the drum wall, said paddles and the portions of the drum wall over which they wipe defining between them acute angles to form spaces in which grapes are crushed, and short flat paddles on the remaining arms of each 40 spider disposed radially of the drum, the last-named paddles being in wiping contact with the drum wall at their outer edges only and comprising carrying paddles for grapes to be crushed, the curved and flat paddles being spaced circumferentially of the drum in an alternating arrangement on each spider, there being substantially wide clear spaces between the paddles of adjacent spiders, all of said paddles being pitched spirally of the drum and the several spiders being spirally staggered longitudinally of the drum; and means for rotating the drum and the main shaft in the same direction but at different speeds.
